US0D1070750S

(12) **United States Design Patent** (10) **Patent No.:** **US D1,070,750 S**
(45) **Date of Patent:** **** Apr. 15, 2025**

(54) **ELECTRIC VEHICLE CHARGING DEVICE**

(71) Applicant: **eTreego Co., Ltd.**, Zhubei (TW)

(72) Inventor: **Shao-Pei Lin**, Zhubei (TW)

(73) Assignee: **eTreego, Co., Ltd.**, Jhubei (TW)

(**) Term: **15 Years**

(21) Appl. No.: **29/883,766**

(22) Filed: **Feb. 2, 2023**

(30) **Foreign Application Priority Data**

Aug. 4, 2022 (TW) 111303848

CLAIM

The ornamental design for an electric vehicle charging device, as shown and described.

DESCRIPTION

FIG. 1 is a perspective view;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the Figures are for the purpose of illustrating portions of the electric vehicle charging device that form no part of the claimed design.

1 Claim, 7 Drawing Sheets
